UNITED STATES PATENT OFFICE

162,892

MINIATURE CAMERA

Franz Sochor, Vienna, Austria, assignor to Otto Brullhard, Forest Hills, N. Y.

Application May 31, 1950, Serial No. 10,264

Term of patent 14 years

(Cl. D61—1)

To all whom it may concern:

Be it known that I, Franz Sochor, a citizen of Austria, residing at Vienna, Austria, have invented a new, original, and ornamental Design for a Miniature Camera, of which the following is a specification, reference being had to the accompanying drawing, forming part thereof.

Fig. 1 is a perspective view of a miniature camera showing my new design and illustrating one side and the back of the camera with the outer lens cover in open position.

Fig. 2 is a similar view, but illustrates the other side of the camera and the front thereof with the lens cover in closed position.

The groups of short heavy dark lines represent surface ornamentation.

I claim:

The ornamental design for a miniature camera, as shown and described.

FRANZ SOCHOR.
